(57) **CLAIM**

The ornamental design for the heat-dissipating radiator for electronic apparatus, as shown and described.

DESCRIPTION

FIG. 1 is a top perspective view of a heat-dissipating radiator for electronic apparatus.

FIG. 2 is a front view thereof.

FIG. 3 is a rear view thereof.

FIG. 4 is a left side view thereof.

FIG. 5 is a right side view thereof.

FIG. 6 is a top plan view thereof.
